STOKER CONSTRUCTION

Royce L. Beers, Detroit, Mich., assignor to Detroit Stoker Company, Detroit, Mich., a corporation of Michigan

Application February 19, 1934, Serial No. 712,066

6 Claims. (Cl. 126—169)

This invention relates generally to grate actuating means and refers more particularly to the means employed for actuating the grates within a furnace or boiler fired by a suitable stoker.

Heretofore such grates have been mounted for tilting movement and have been actuated from the front of the furnace by a shaking bar suitably connected to the grates and extending through an opening in the front wall of the furnace, and a rocker member pivotally connected to the shaking bar at the outer forward end thereof and operable by a suitable hand lever. Inasmuch as the actuator for the shaking bar was a rocker member and was pivotally connected thereto, the opening in the front wall of the furnace that received the shaking bar had to be sufficiently large to permit the shaking bar to move vertically as well as longitudinally upon oscillation of the rocker member. As a result, a large portion of the air fed into the furnace beneath the grates escaped through this opening instead of passing upwardly through the grates and fuel bed thereon to assist in the proper combustion of the fuel.

Therefore, it is an object of the present invention to provide a grate actuating means wherein fluid actuated means instead of the rocker member and lever is utilized for actuating the shaking bar.

Another object is to provide a grate actuating means wherein an element of the fluid actuated means restricted to longitudinal movement only is movable through the front wall of the furnace and is operatively connected to the shaking bar for the grates.

Another object is to provide a grate actuating means wherein the connection between the element of the fluid actuated means and shaking bar is such that the shaking bar may move vertically and longitudinally while the element is moving longitudinally.

Another object is to provide a grate actuating means wherein an enclosure for a part of the fluid actuated means serves to effectively close and seal the opening in the front wall of the furnace through which the fluid actuated element extends.

Other objects, advantages and novel details of construction of this invention will be made more apparent as this description proceeds, especially when considered in connection with the accompanying drawings, wherein:

Figure 1 is a fragmentary vertical sectional view through a furnace containing tiltable grates and showing the means embodying my invention for actuating said grates;

Figure 2 is a sectional view taken substantially on the line 2—2 of Figure 1;

Figure 3 is a fragmentary front elevation of the cylinder, control valve and associated pipes;

Figure 4 is a top plan view of the cylinder, control valve and associated parts with portions broken away and in section;

Figure 5 is a perspective view of the lever H and showing associated parts in dotted lines.

Referring now to the drawings, A are the 10 grates, B is the shaking bar, and C designates generally the means embodying my invention for actuating the bar B.

As shown, the grates A are conventional in configuration and are located in a suitable furnace between the combustion chamber D and ash pit E thereof. Preferably the grates A are non-rotatably mounted on bars F which in turn are rotatably mounted in a suitable supporting frame G. H are levers non-rotatably mounted on the 15 bars F and pivotally connected to and carrying the shaking bar B. Thus, the levers H will tilt the grates A about the axes of the bars F when the bar B is moved longitudinally.

Preferably the means C for moving the shaking 25 bar B longitudinally comprises a reciprocating piston I within a cylinder J upon the front wall K of the furnace, a rod L rigid with the piston I and extending through an opening M in the front wall K of the furnace, and a link N terminally 30 connected to said rod L and bar B.

As shown, the cylinder J is provided at opposite ends with suitable heads O and P respectively, and is provided in the top thereof adjacent said heads with fluid openings 1 and 2 respectively. Preferably the rear head O is bolted to the rear end of the cylinder and constitutes a closure therefor, while the forward head P has a flange portion 3 secured by bolts 4 to a flange 5 at the forward end of the cylinder and has a reduced cylindrical 40 portion 6 that extends through the opening M in the front wall K of the furnace and serves as a guide for the rod L. Preferably the flanges 3 and 5 cover the opening M in the front wall K and are secured to the outside metal plate R thereof by the bolts 4. A gasket 7 is interposed between the flange 3 and plate R to effectively seal the opening M about the reduced portion 6 and thus prevent the escape at this point of air fed into the furnace beneath the grates A.

To prevent the escape about the rod L of the fluid used in the cylinder J for actuating the piston I, suitable packing S is placed within a chamber 10 in the reduced portion 6 and is held 55

in operative position therein by a gland T secured by bolts U to the cylindrical portion 6.

In the present instance steam is preferably used as the fluid for actuating the piston I and 5 is conducted from a suitable source by a pipe 11 to a four-way valve W. Pipes 12 and 13 respectively extend from the valve W to the openings 1 and 2 in the cylinder, while a pipe 14 extends from the valve and constitutes an exhaust 10 line. The valve W may be any suitable construction and may be operated by any suitable means. Preferably the valve has a rotary plug 16 provided with passages 17 for establishing communication with the pipes 11, 12, 13 and 14, as illustrated in Figure 4 and is operated by a suitable 15 lever X.

In use when one passage 17 communicates with pipes 11 and 13, the other passage 17 will communicate with the pipes 12 and 14, hence the 20 steam will enter the cylinder J at the forward end thereof and will move the piston I, rod L, link N and bar B rearwardly. As a result, the 25 grates A will be rocked about the axes of the bars F to dumping position. When one passage 17 communicates with pipes 11 and 12, the other passage 17 will communicate with pipes 13 and 14, hence steam will enter the cylinder J at the 30 rear end thereof and will move the piston I, rod L, link N and bar B forwardly. As a result the grates A will be restored to their normal horizontal position.

Thus, from the foregoing it will be apparent that the grates A will be moved positively to and from dumping position. Inasmuch as the rod 35 L is restricted to longitudinal movement only, the opening M in the front wall K of the furnace may be smaller as it is unnecessary to provide clearance at this point to compensate for any vertical movement as heretofore. Moreover, the 40 link connection between the rod L and bar B permits the latter to move vertically as well as longitudinally. It will also be observed that the head P not only forms a guide for the rod L to restrict its movement, but also cooperates 45 with the gasket 7 to effectively seal the opening M in the front wall of the furnace so that air fed into the ash pit E beneath the grates will be prevented from escaping about the cylindrical portion 6 through the front wall of the furnace.

50 What I claim as my invention is:

1. In a stoker, the combination with a stoker

wall having an opening therethrough, a movable grate member on one side of the wall, a cylinder upon the wall closing and sealing the wall opening, a piston within the cylinder and a connection between the piston and grate member.

2. In a stoker, the combination with a stoker 10 wall having an opening therethrough, of a movable grate bar within the stoker, a fluid cylinder mounted directly upon the wall and sealing the opening, a piston within the cylinder, its rod extending through the opening, and a link connection between rod and grate bar.

3. In a stoker, the combination with a stoker 15 wall having an opening extending therethrough, of a movable grate bar within the stoker, a fluid cylinder mounted upon the exterior of the wall and sealing the wall opening, a tubular extension upon the cylinder projecting through the opening forming a centering means for the cylinder 20 and a piston rod guide, a piston within the cylinder, a rod for the piston working within the cylinder extension, and an operative connection between said rod and grate bar.

4. In a stoker, the combination with a stoker 25 wall having an opening therethrough, of a movable grate bar within the stoker, a fluid cylinder mounted upon the wall and sealing the opening, an extension upon the cylinder engaging the 30 wall opening and forming a centering means for the cylinder, a piston within the cylinder, and an operative connection between piston and grate bar.

5. In a stoker, the combination with a stoker 35 wall having an opening extending therethrough, of a movable grate bar, a fluid cylinder equipped with fluid control valve mechanism mounted in its entirety upon the wall and sealing the opening therethrough, a piston within the cylinder, and a rod for the piston connecting with the 40 grate bar.

6. In a stoker, the combination with a stoker 45 wall having an opening extending therethrough, a plurality of rockable grate bars within the stoker, a shaker bar for the several grate bars, a fluid cylinder mounted upon the exterior of the 50 wall and sealing the said opening, a piston within the cylinder, its rod extending through the wall opening, and a link connecting said rod with the shaker bar.
